UNITED STATES PATENT OFFICE.

STEPHEN SCANLON, OF NEW YORK, N. Y.

BRIDGE PIECE.

Application filed May 6, 1924. Serial No. 711,391.

To all whom it may concern:

Be it known that I, STEPHEN SCANLON, a citizen of the United States, and a resident of the city of New York (borough of the Bronx), in the county of Bronx and State of New York, have invented new and Improved Bridge Pieces, of which the following is a full, clear, and exact description.

This invention relates to bridge pieces, 10 and more particularly to improved means for bridging the floor joists, studding and other building structures to take the place of the ordinary wooden bridging heretofore in use.

15 A further object is to provide a bridge piece which can be manufactured and sold at an extremely low price, which can be quickly placed in position, and which will securely hold the joists or studding in proper parallel relationship.

With these and other objects in view, the invention consists in certain novel features of construction and combinations and arrangements of parts which will be more 25 fully hereinafter described and pointed out in the claims.

In the accompanying drawings—

Figure 1 is a view in vertical section illustrating my improved bridge pieces in operative position on the floor joists;

Figure 2 is a view in section on the line 2—2 of Figure 1;

Figure 3 is a perspective view of one of the bridge pieces.

35 While I illustrate in the drawings my improved bridge pieces 1 as located at the lower edges of the joists 2 it is obvious that they may be located at the upper edges of the joists and also that these bridge pieces 40 are adapted for use with equal facility for vertical studding or other spaced timbers in any building structure where it is desired to equally space such joists, studs or timbers, and I have illustrated and will describe the same in connection with floor 45 joists merely to show one use of my improved bridge pieces.

In constructing my improved bridge piece I employ a strip of metal of suitable gauge, and then the ends of the strip are bent at right angles forming tongues 3 with the extremities of said tongues bent inwardly and at acute angles forming gripping jaws 4,

the latter being serrated at their extremities forming a plurality of biting teeth 5 which 55 are adapted to bite into the material of the joists, studding or timbers and securely hold the same.

In use it is simply necessary to locate the bridge piece over a pair of joists or studding and then force the same inwardly so that the teeth 5 will bite into the material of the joists or studding and will securely hold.

By arranging the bridge pieces as indicated, that is, in a general staggered relation, one bridge piece engaging a pair of joists, and the next bridge piece engaging one of said pair of joists and the next joist, and so on throughout the structure. By 70 reason of this arrangement the joists are held against movement and are maintained parallel. Furthermore, this operation can be quickly done and absolute uniformity had, leaving nothing to guesswork or to 75 imperfection in workmanship.

By reason of this construction of bridge piece any tendency of the joists to spread only serves to cause the toothed jaws to bite more firmly into the joists and prevent such 80 movement.

While I shall hereinafter refer in the claims to the parts to which the bridge pieces are secured as joists I would have it understood that I employ this term in its broadest possible sense to include any arrangement of parallel studs, timbers and the like with which my improved devices are adapted for use.

Various slight changes and alterations 90 might be made in the general form of the parts described without departing from my invention, and, hence, I do not limit myself to the precise details set forth but consider myself at liberty to make such slight 95 changes and alterations as fairly fall within the spirit and scope of the appended claims.

I claim:

1. A bridge piece of the character described, comprising a strip of metal, tongues 100 projected at right angles to the ends of said strip, inwardly projected jaws at the ends of the tongues, said jaws located at an acute angle relative to the tongues, and teeth at the extremities of said jaws.

2. In combination with a series of joists,

bridge pieces composed of strips of metal, tongues at right angles to the ends of said strips, toothed jaws at the extremities of said tongues projected at an acute angle to the tongues, each strip located against the edges of a respective pair of joists with the jaws engaging the faces of said joists, and

other bridge pieces engaging one of the pairs of joists and the next joist in like manner, and said bridge pieces having staggered arrangement and lying flat against the edges of the joists and at a right angle thereto.

STEPHEN SCANLON.
